DESIGN FOR A RING.

No. 38,465.

Specification for Design.

Patented Feb. 26, 1907.

Application filed August 1, 1906. Serial No. 328,804. Term of patent 14 years.

To all whom it may concern:

Be it known that I, FRANK C. WIDMANN, a citizen of the United States, residing at Cleveland, in the county of Cuyahoga and State of Ohio, have invented a new, original, and ornamental Design for Rings, of which the following is a specification, reference being had to the accompanying drawing, forming a part thereof.

In the drawing, Figure 1 is a perspective view showing one end of the design. Fig. 2

is a front elevation showing the central part of the design, and Fig. 3 is a perspective view showing that end of the design that is opposite that shown on Fig. 1.

I claim—

The ornamental design for a ring, as shown.

FRANK C. WIDMANN.
